UNITED STATES PATENT OFFICE.

FRANK S. DAVIS, OF HOMEWOOD, ILLINOIS, ASSIGNOR TO AUSTIN MANUFACTURING CO., OF CHICAGO, ILLINOIS, A CORPORATION OF ILLINOIS.

ROAD-ROLLER-ENGINE MOUNTING.

Application filed April 28, 1923. Serial No. 635,205.

To all whom it may concern:

Be it known that I, FRANK S. DAVIS, a citizen of the United States, residing at Homewood, in the county of Cook and 5 State of Illinois, have invented a certain new and useful Improvement in Road-Roller-Engine Mountings, of which the following is a specification.

This invention relates to heavy engine 10 driven road rollers used for working in the streets. In a machine of this class, there is always a front roller mechanism rotatable upon a vertical pivot sustained by a sort of a yoke at the front of a relatively 15 wide frame supported at its rear by one or more rollers and carrying in front of the rear roller an engine for propelling the entire machine.

The space for the engine of such a machine is comparatively limited and it is, therefore, exceedingly difficult to do machine work or the like in preparation for the engine after the road roller frame is assembled.

25 The object of this invention is to provide a frame construction and particularly a rigid spacing engine carrying base member interpositioned between the frame side members of such a character that it carries substantially all shaft bearings, etc., necessary for the reception of the engine—this so that all machine work on such parts necessary for the engine can be done upon this spacing or base member before the road 30 roller frame is assembled, thus insuring perfect alignment of all bearings for each given shaft of the engine.

The invention consists in mechanism capable of attaining the foregoing objects; 40 which can be easily and cheaply made, which is satisfactory in use and is not readily liable to get out of order.

More particularly, the invention consists in numerous features and details of construction which will be hereafter more fully 45 set forth in the specification and claim.

Referring to the drawings in which like numerals designate the same parts throughout the several views;

50 Figure 1 is a side elevation of a complete road roller equipped with the mechanism of this invention.

Figure 2 is a transverse side view taken on the irregular line 2—2 of Figure 3.

Figure 3 is a transverse sectional view 55 on the line 3—3 of Figure 1.

Figure 4 is a plan view taken on the irregular line 4—4 of Figure 1.

Figure 5 is a perspective view of the frame mechanism without the engine applied thereto, taken from the rear of Figure 1 or from the top of Figure 4.

The drawings show a conventional form of two wheel roller mounted upon a rear roller 10 and a front roller 12, the latter 65 journaled on a horizontal axis at 14, adapted for rotation on a vertical axis 16 in an arched yoke 18 carried by two widely separated side members 20 and 22 passing across opposite ends of the roller 10, said 70 side members carrying at their rear a conventional form of water tank 24 placed above a separating cross-member 26, not entering into this invention. These side members 20 and 22 are sustained from the 75 shaft 28 of roller 10 by suitable bearings 30 and 32, the former attached directly to side member 22, as shown in Figures 4 and 5.

Interposed between side members 20 and 22, and preferably immediately adjacent to the yoke 18, is a spreader engine base casting 34 filling the longitudinal space between said members 20 and 22 and having an L-shaped extension 36 extending down one side member, as 20, beyond shaft bracket 85 32 which it carries, as clearly shown in Figure 5.

Rising from the main body portion 34 of this L-shaped base are a plurality—in the particular case here illustrated three shaft 90 supports 38—40 and 42 affording aligned bearings 44 for the main drive shaft 46 of the conventional form of engine mechanism 48 indicated in Figures 1, 2 and 3, said shaft 46 carrying between bearing supports 95 40 and 42 conventional reversing gear mechanism 50—52 and 54 not entering in detail into this invention and carrying between bearing supports 38 and 40 conventional 100 form of changed speed gear mechanism 56—58, two of whose gears 60 and 62 are mounted upon a shaft 64, journaled in shaft bearing brackets 66 on member 34 and 68 on member 36. The engine base member 34 is provided with such vertically disposed perforations 70 as may be necessary for the

reception of bolts 72 which hold the engine 105 48 in proper position to render it an opera-

2
tive structure in connection with the shafts 46 and 64 and their attached mechanisms heretofore described. Shaft 64 carries suitable gears 74, meshing with an annular gear 76, carried by roller shaft 28 and therefore capable of propelling rear roller 10.

By providing the one-piece spacing engine base member 34-36 which can be interposed as a unit between the frame side members 20 and 22, and placing all of the necessary shaft bearings for the engine mounting on this base member, all of the machine work necessary to accurately position shafts 46 and 64 and their cooperating mechanisms in connection with the engine can be done in the machine shop before the road roller frame is assembled, thus doing away with machine work in the field or assembly shop, insuring a much more accurate piece of work than has heretofore been possible in the art and greatly reducing the expense of the finished road roller. In assembling the mechanism, the parts may be first placed in the position of Figure 5, the frame member 34-36 being secured in place by suitable bolts or screws applied through suitable perforations 78 and 80, provided

for them, and the engine thereafter assembled in connection with the frame or the engine may be mounted upon the frame member 34-36 in the shop and the thus assembled parts applied as a unit between the side members 20-22 and bolted to place.

Having thus described my invention, what I claim as new and desire to secure by Letters Patent is:

In combination with two widely separated side members terminating in a yoke for sustaining a front wheel of a road roller, a unitary L-shaped base for an engine for a road roller, interposed between side members immediately behind said yoke, one arm of the base extending along an adjacent side member away from said yoke, said base carrying on both its arms a multiplicity of shaft brackets integral therewith, certain groups of said brackets being for certain particular shafts of the engine mechanism and prepared, therefore, before the parts are assembled.

In witness whereof, I have hereunto subscribed my name.

FRANK S. DAVIS.
